**COMBINED MAP GLOBE AND SUPPORT
THEREFOR**

Raphael Katzen, Cincinnati, Ohio

Application August 9, 1954, Serial No. 31,780

Term of patent 14 years

(Cl. D25—1)

Fig. 1 is a top plan view of a combined map globe and support therefor, showing my new design.

Fig. 2 is a side elevational view thereof; and

Fig. 3 is a perspective view thereof.

The dominant features of my design reside in those portions shown in full lines.

I claim:

The ornamental design for a combined map globe and support therefor, as shown and described.
